UNITED STATES PATENT OFFICE.

OLIVER TATRO, OF ATTAWAUGAN, CONNECTICUT.

UMBRELLA.

1,057,897.

Specification of Letters Patent.

Patented Apr. 1, 1913.

Application filed October 22, 1912. Serial No. 727,091.

To all whom it may concern:

Be it known that I, OLIVER TATRO, a subject of the King of Great Britain, residing at Attawaugan, in the county of Windham and State of Connecticut, have invented certain new and useful Improvements in Umbrellas, of which the following is a specification, reference being had therein to the accompanying drawing.

10 This invention relates to umbrellas and has special reference to a detachable cover therefor, in combination with a simple and efficient means for attaching the cover to the frame of the umbrella.

15 Another object of this invention is the production of a plurality of portions struck from the rib for holding the button which attaches the cover to the frame.

With these and other objects in view, this 20 invention consists of certain novel combinations, constructions, and arrangements of parts, as will be hereinafter fully described and claimed.

In the accompanying drawing: Figure 1, 25 is a view of an umbrella as constructed in accordance with this invention, the cover being applied thereto. Fig. 2, is a side elevation of a portion of a rib showing the attaching means carried thereby. Fig. 3, is a 30 transverse section taken through the attaching means and rib. Fig. 4, is an enlarged detail view showing the rib and struck out portion. Fig. 5, is a view showing a button hole in the cover.

35 Referring to the accompanying drawing by numerals it will be seen that the device consists of the usual staff 20, handle 21, and

ribs 23. In connection with the frame there is provided a cover 25 having button holes 26 at the end of each seam. Each rib 23 has 40 certain portions struck out and bent upward as at 38. These portions are formed adjacent the outer end of the rib 23 and are bent back upon the rib so as to extend in the same plane as the rib, whereby the portions are 45 able to stand a considerable strain without bending in the middle. The outer ends of the struck out portions are provided with a rivet 39 which passes through the eye 40 of the button 41. The umbrella cover is provided with a centrally disposed opening secured to a ring 42 arranged to fit upon the staff 20 and it will be seen that by slipping this ring over the point of the staff 20 and buttoning the cover on to the button the 55 same may be readily placed on the frame and by reversed operation may as readily be removed.

Having thus described the invention what 60 is claimed as new, is:

The combination with an umbrella rib provided with portions struck from the sides of said rib, said portions bent upwardly and back upon said rib so as to extend in the same plane as said rib whereby to relieve the 65 strain upon said portions, and a button carried by the upper ends of said portions.

In testimony whereof I hereunto affix my signature in presence of two witnesses.

OLIVER TATRO.
